This invention relates to a design for the

20 As herein shown, the shank of the handle curves inward from its junction with the bowl, then tapers gradually outward to a point *a*, where it curves inward and then outward, forming an oval section *b*, surmounted by a
25 crown *c*. The ornamentation of the handle consists of a medallion *A*, set in the oval sec-

tion *b*, surrounded by scrollwork *B*, surmounted by a small medallion *C*, set in the crown *c*, and surrounded by a scroll and leaf ornamentation *D*. At the outward curve *a* 30 of the handle is a small oval medallion *E*, surrounded by scrolls *F*, having foliations *G* rising to the scrollwork *B* above, and similar foliations *G'* depending upon the tapered shank of the handle, the ornamentation of 35 which consists of elongated scrolls *H*, inclosing the central portion of the shank and forming the junction between the shank of the handle and bowl, all as shown in the accompanying illustration. 40
